UNITED STATES PATENT OFFICE.

CATALDO COLETTI, OF OLEAN, NEW YORK.

SANITARY MASK.

Application filed July 8, 1922. Serial No. 573,588.

To all whom it may concern:

Be it known that I, CATALDO COLETTI, a citizen of the United States, residing at Olean, in the county of Cattaraugus and State of New York, have invented new and useful Improvements in Sanitary Masks, of which the following is a specification.

This invention relates to sanitary devices and has for its object the provision of a novel mask designed primarily to be worn by workers in places where there is a great amount of dust, the device being for the purpose of purifying the air so that the dust will not be breathed in.

15 An important object is the provision of a device of this character which encloses the nose and mouth of the wearer and which is provided with novel fastening means engaging the ears for holding it in place.

20 Another object is the provision of a device of this character which is provided with novel air filtering means, the filtering means being capable of saturation by disinfectant so as to render the device advantageous for use by nurses, doctors and others coming in contact with contagious diseases, the device being furthermore of great benefit when worn by surgeons for removing germs and impurities from their exhalations 25 and preventing possible infection of a patient operated upon.

An important object is the provision of a device of this character which will be simple and inexpensive in manufacture, which may be worn continuously without discomfort, which is operable to permit ready removal of the filtering medium and which will be a general improvement in the art.

With the above and other objects and advantages in view the invention consists in the details of construction to be hereinafter more fully described and claimed and illustrated in the accompanying drawings, in which:

45 Figure 1 is a front elevation of my device in applied position,

Figure 2 is a side elevation,

Figure 3 is a detail longitudinal section through one of the filtering members,

50 Figure 4 is a cross section therethrough,

Figure 5 is a detail section through an edge of the shell of the device.

Referring more particularly to the drawings I have shown my device as comprising 55 a partially spherical shell 10 of some light material such for instance as thin sheet alu-

minum. This shell is so cut and formed at its open side as to fit conformingly over the bridge of the nose, against the cheeks and beneath the chin of the wearer and it is preferable that the free edge carry a rubber binding 11 which includes a tubular face engaging portion 12 which will operate as a pneumatic pad for making a substantially air tight joint against the skin while avoiding any discomfort. This binding is grooved as shown at 13 for frictional engagement upon the edge of the shell as shown most clearly in Figure 5.

It is of course conceivable that this shell 70 might be held in place by anyone of various means though in actual practice I prefer to provide straps 14 at each side of the shell engageable about the wearer's ears, these straps being provided with adjusting buckles 75 15 so that the device may be made to fit upon different persons.

The shell is provided at opposite sides with openings over which are secured the flanged edges 16 of conduit members 17 80 which are tubular in form, and which have their outer ends reduced as shown at 18 to define shoulders 19. Detachably associated with each conduit member is a filtering device comprising a tube 20 having one end 85 enlarged as shown at 21 and formed with a curved flange 22 adapted to engage about the reduced extension 18 and containing a rubber gasket 23 operating to make a tight fit with the associated conduit member. Secured within the enlarged portion 21 is a flanged member 24 to which is secured a disk 25 of gauze. Located within the tube 20 is absorbent material 26 which may be a sponge or which may be some other material capable of being saturated with liquid. The outer end of each tube 20 is closed by a flanged ring 27 which is covered by gauze 28.

In the operation of the device it is intended that the sponge or other absorbent material 26 be saturated with water. When the device is secured upon the face of the wearer it is apparent that respiration is through the filtering members. The gauze 105 28 will operate to remove the major portion of the dust, the sponge 26 will remove most of what passes by the gauze 28 and the very fine gauze 25 will still further exert a purifying effect so that by the time air drawn into the device is inhaled by the wearer it 110 will be free from all dust and dirt, so that

the wearer will be safe guarded from the injurious effects of working in a very dusty place such as a cement works, quarry, marble yard, coal mine or the like.

5 When the device is to be worn by nurses, doctors and others, the sponges or other absorbent material would naturally be saturated with disinfectant so as to protect the wearer against contagion. In case of a 10 surgeon the device would operate also to remove impurities and germs from his breath to prevent possible infection of an incision during an operation, especially as the tubular air conduits face toward the back of 15 the head.

From the foregoing description and a 20 study of the drawings it will be apparent that I have thus provided a very simply constructed and easily applied sanitary mask which will be a great convenience 25 under many conditions and which may be worn without discomfort. As there are no moving parts it is apparent that there is nothing to get out of order so that the device should have a long life.

While I have shown and described the preferred embodiment of the invention it is of course to be understood that I reserve the

right to make such changes in the form, construction and arrangement of parts as will not depart from the spirit of the invention or the scope of the subjoined claim.

Having thus described my invention I claim:

In a device of the character described, a 25 shell member adapted for engagement upon the lower portion of a person's face to enclose the nose and mouth, conduit members 30 communicating with the interior of said shell and having flaring attaching portions 40 secured externally upon the shell, said conduit members having reduced ends defining shoulders, a tubular receptacle containing absorbent material and having one end enlarged to form a shoulder, said enlarged 45 portion being bulged outwardly for engagement upon the reduced end of the conduit and containing a packing gasket, a screen 50 carrying frame located within said receptacle and engaging against the second named shoulder and the adjacent reduced end of the conduit, and a screen carrying rim screwed on the other end of the receptacle.

In testimony whereof I affix my signature.

CATALDO COLETTI.
